UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS. A CORPORATION OF ILLINOIS.

CHAIN-SEVERING DEVICE FOR SEWING-MACHINES.

1,118,589.

Specification of Letters Patent.

Patented Nov. 24, 1914.

Application filed January 2, 1906. Serial No. 294,256.

To all whom it may concern:

Be it known that I, DUDLEY S. SEYMOUR, a citizen of the United States, residing at Oak Park, in the county of Cook, State of Illinois, have invented certain new and useful Improvements in Chain-Severing Devices for Sewing-Machines, of which the following is a description, reference being had to the accompanying drawing and to the letters and figures of reference marked thereon.

This invention relates to sewing machines of that general class employed for the sewing of bags or other articles, wherein the articles are united by a continuous chain of stitching, which must afterward be severed at points between the articles.

The principal object of the invention is to provide a cutting mechanism, in combination with means for automatically feeding the loose chain between the cutters.

A further object of the invention is to provide a chain-depressing mechanism that is normally held elevated by the bags or other articles being stitched.

A still further object of the invention is to provide a chain-depressing mechanism that is associated with the presser foot in such manner that when the presser foot is raised, the chain-depressing device will also be raised, and will be automatically locked and held in elevated position.

A still further object of the invention is to provide a chain-cutting attachment for machines having a top feed.

A still further object of the invention is to provide means for holding the chain from backward movement during the return of the feed dog to the front position.

A still further object of the invention is to provide a sewing machine of this type having a top feeding member so arranged and constructed as to permit of the application of a chain-depressing member.

With these and other objects in view, the invention consists in the novel construction and arrangement of parts hereinafter described, illustrated in the accompanying drawings, and particularly pointed out in the appended claims, it being understood that various changes in the form and proportions of parts, and minor details of construction may be made without departing from the spirit of the invention.

Referring to the drawings: Figure 1 is a front elevation of a sewing machine embody-

ing the invention; Fig. 2 is an end elevation of the same, drawn upon an enlarged scale; Fig. 3 is a rear elevation of the machine; Fig. 4 is a detail perspective view, illustrating the principal portions of the chain-depressing and cutting devices; Fig. 5 is a transverse sectional view in the plane of the needle, showing the arrangement of the chain-depressing and cutting devices in operative position; Fig. 6 is an elevation, illustrating the chain-depressing mechanism and presser foot in an elevated position; Fig. 7 is a detail view, looking from the inner side of the presser foot and showing the manner in which the chain-depressing device is held elevated by the passing bag or other article; Figs. 8 and 9 are detail sectional views on the lines 8—8 and 9—9 respectively, of Fig. 2; and Fig. 10 is a perspective view of a modified form of chain depressor for use on a two needle machine.

Similar numerals of reference indicate corresponding parts throughout the drawings.

The frame of the machine embodies the usual goose neck A and bed plate B, while the stitch-forming mechanism may be of the type ordinarily employed in machines of this class, the feed block, however, being slightly modified in order to permit the depression of the chain between the articles.

The forward end of the throat plate 10 is provided with the usual slots for the passage of the feed block 12 and the needle, and in rear of the main feed block 12 is arranged a supplemental feed block 13, that is secured to the reciprocatory carrying arm 14, both the feed block members, receiving uniform movement. The feed block 13 is arranged to operate in a slot 15 formed in the rear end of the throat plate, and between the two slots 11 and 15 there is sufficient space for the depression of the loose chain between the adjacent articles. The supplemental feed block 13 is further provided with a centrally disposed slot for the passage of a chain-depressing foot 17, which has a grooved lower face for engagement with the loose chain.

The main presser foot 18 is carried by a presser bar 19, of ordinary construction and may be raised to inoperative position by the usual handled cam 20. This presser foot is open for the reception of a top feed bar 21, that is free to slide to and fro within the

presser foot, and is held in proper position with respect to the base of the foot by means of a small anti-friction roller 22, journaled in the side walls of said presser foot.

5 The top feed bar is provided with an elongated slot 23 to permit the free passage of the needle and its rear end is provided with a slot 24 for the passage of the chain-depressing foot. This chain-depressing foot 10 carries a pin 17' which engages against the upper face of the top feed bar and limits downward movement of the chain depressor. At the same time, the pin, resting on the bar, is raised with the latter when the presser 15 bar is elevated. The rear end of this feed bar is bent upward at an obtuse angle to the plane of the throat plate, and thence extends in a generally vertical plane, its upper end being provided with a forwardly extending 20 toe 25, that is adapted to engage with a lug 26 projecting from a supplemental presser bar 27, guided vertically in lugs 28, projecting from the head of the machine, and connected with the main presser bar 19 by a 25 pin 29. The feed bar is provided with a reinforcing rib 30, that extends from the point adjacent to the rear end of the presser foot, to a point adjacent to the toe 25.

The rear face of the top feed bar is provided with a projecting lug 32, to which is connected the lower end of a telescopically adjustable rocker arm 33, the upper end of said arm being rigidly secured to a shaft 34, that is mounted in bearings formed in lugs 35 35 projecting from the rear face of the goose neck. To the rear end of this shaft is secured a rocker arm 36, having an arcuate slot 37 for the reception of a pin 38, which may be locked in any adjusted position, the 40 regular distance between the axis of the shaft and the axis of the pin 38 being adjusted in accordance with the feed desired.

On a pin 38 is mounted the upper end of a connecting rod 39, that extends down 45 through a slot or recess in the bed plate of the machine, and carries an eccentric strap 40, that is operated by an eccentric 41 on the main shaft C.

To the lower portion of the presser foot 50 bar is secured a block 44, that is provided with a bearing for the shaft 42, at the rear end of which is mounted the chain-depressing foot 17, that is held down in engagement with the chain by means of a spring 55 42'. This chain-depressing foot is in the form of a bent arm at the outer or lower end of which is a widened or lengthened foot member having a grooved lower face to receive and guide the chain, and extending 60 transversely across this presser foot is a notch or groove 46, which, when the foot is depressed, serves to receive and permit free action of the chain cutting blade. This depressor may also be provided with two or 65 more grooves for use in connection with a

70 machine making two or more chains of stitches. To this depressing foot is secured a cam 47, having a lower rounded face that is arranged to one side of the presser foot immediately to the rear of the needle, and is 75 designed to ride on top of the bag or other article being stitched. This cam is arranged immediately above a curved recess 48, that is formed at one side of the throat plate, and in operation, the fabric will be bridged across 80 this notch or recess, and the cam will ride freely on top of the fabric, and will hold the depressing foot slightly above and out of contact with the chain of stitching and the fabric. It is only when the cam is unsupported, that is to say, when the end of one 85 article passes beyond it, that the cam descends, and allows similar movement of the depressing foot, the latter then acting to force the loose or free chain of stitching 90 downward through the slot 15 into engagement with the cutting devices.

95 Secured to the lower portion of the head of the machine is a block 52 carrying a stud 53, on which is mounted an arm 54, which is 90 depressed by a coiled spring 53' surrounding the stud, and having one end secured to the frame and the other end to said arm. The lower end of the arm 54 rests on the fabric at a point slightly in advance of the depressing foot, and its lower face is in horizontal alignment with the lower face of said foot. When elevated, the arm will cause the depressor to swing on its pivot and the lower end of the arm will enter the transversely 100 disposed notch or recess 46, and positively lock said foot in the elevated position shown in Fig. 6.

In order to lift the depressing foot, when the top feed and presser foot are elevated, 105 the block 44 is provided with a cam 56, arranged to engage the lower edge of the arm 54, and as the presser foot bar moves upward, this cam raises the arm 54, moving the latter from the position shown in Fig. 110 5 to that shown in Fig. 6, and finally interlocking therewith, in order to hold said foot in elevated inoperative position. During the upward movement of the feed dog, the presser foot is pushed up and cam 56 then 115 acts to slightly raise the arm 54, releasing the chain clamped or held by said arm, so that it may be fed forward. When the feed dog descends the arm 54 again moves down against the chain, and clamps it against the 120 work support.

125 Immediately below the throat plate is arranged a fixed cutting blade 60, the cutting edge of which is slightly in rear of the forward edge of the slot 15. On the lower portion of the bed plate is secured a block 61, forming a bearing for the transversely disposed shaft 62, to which is secured a rocker arm 63. The upper end of the rocker arm 63 is grooved for the reception of an 130

adjustable blade 64. A screw 64^a clamps the blade 64 against one wall of the groove in the arm 63 and by releasing this screw the blade may be adjusted. The inner end of the shaft 62 is provided with a rocker arm 65, having a ball-shaped end that fits within a suitable socket formed in the connecting rod 66. At the other end of the connecting rod is an eccentric strap 67, surrounding an eccentric 68 on the main shaft C of the machine.

In the operation of the device, movement is transmitted to the blade 64, so long as the stitching operation progresses, and the parts being in the position shown in Fig. 7, the depressing foot 17 is held slightly elevated above the line of stitching in the fabric by the elevating cam 47. While any fabric remains under this cam 47, the depressing foot 20 will be inoperative, but as soon as the end of a bag or other article passes from under the cam, the latter will fall, and the depressing foot will force the free chain of stitching down through the slot 15, that portion of the chain which bridges the slot 15 being forced between and severed by the knives. As the cutter operates continuously, the chain is clipped as long as it is held depressed, and the articles of thread so severed, 30 fall through an opening 70 in the frame and thence pass through the similar opening in the table or other support on which the machine is mounted.

During the operation of the machine, the 35 rear portion 13 of the feed dog serves to engage the piece of fabric after it has passed beyond the stitch-forming mechanism, and carry it by the cutter and in so doing hold the chain taut between the throat plate 40 needle hole and the fabric, but just as soon as the rear feed dog stops feeding the goods the chain becomes slack and the depressor then carries the chain down to the cutters. The location of the cutter being between the 45 rear feed dog and the throat plate needle hole, it thus leaves a chain of thread upon the piece of fabric that has been stitched, and also leaves a chain of thread on the front of the fabric that is being stitched, or, 50 in other words, a portion of the chain is left at the beginning and ending points of the sewing. This is necessary, as with the chain stitch machine, it prevents the raveling back of the stitches.

55 It will thus be seen that the stitching operation may progress continuously while the bags or other articles are severed.

Having thus described my invention, what I claim as new and desire to secure by Letters Patent, is:—

1. In a sewing machine, stitch-forming mechanism, feeding mechanism, mechanism for severing the threads including relatively moving members, and a device to deliver the 65 thread to the severing mechanism, said de-

vice being controlled by the articles being stitched.

2. In a sewing machine, chain stitch-forming mechanism, a cutting device, and means to operate it, means to deliver the thread to the cutter, and means under control of the fabric for raising and lowering said delivering means.

3. In a sewing machine, stitch-forming mechanism, mechanism for severing the thread including relatively moving members, a device for delivering the thread to the cutter, said delivering device being arranged to operate in a vertical plane and being controlled by the articles being stitched.

4. In a sewing machine, mechanism for severing the thread including relatively moving members, a device controlled by the articles being stitched for delivering the thread to the severing mechanism, said delivering device having means to hold the thread in position on its operative face.

5. In a sewing machine, stitch-forming mechanism, a device for severing the thread and means to operate it, means to deliver the thread to the severing device, including a controlling arm engaging the fabric, said fabric-engaging arm having its face engaging the fabric shaped to offer the least resistance to the passage of the material being stitched.

6. In a sewing machine, stitch-forming mechanism, a work support having a throat plate, a presser foot, a device for severing the thread, means for delivering the thread to the severing device, said presser foot and throat plate being provided with a slot in which said thread-delivering means operate.

7. In a sewing machine including a needle and bed plate, a device for severing the thread located on one side said bed plate, a device engaging the thread to deliver it to the cutter, said thread-engaging device being located on the opposite side of said bed plate and adapted to carry the thread from one side the bed plate to the other side thereof.

8. In a sewing machine, stitch-forming mechanism, a cutting device, means to deliver the thread to the cutting device and automatic means regulated by the passage of the fabric to control the action of the thread delivering means, whereby articles may be stitched and the connecting threads between the same severed.

9. In a chain stitch sewing machine, a cutting device for severing the thread between successive articles, means to deliver the thread to the cutting device, and means in engagement with the material being stitched to prevent the delivery of the thread to the cutting device by said delivering means until the material has passed the stitch-forming device.

10. In a chain stitch sewing machine,

means to form successive stitches after the material being stitched has passed the stitch-forming device, means to feed said stitches forward, a cutting device at one side of the line of feed, and means to operate it, and means to deliver said successive stitches to the cutter.

11. In a chain stitch sewing machine, means to form successive stitches after the material being sewed has passed the stitch-forming mechanism, means to feed said stitches forward, means located in rear of said stitch-forming mechanism and at one side the line of feed to sever said stitches, means for delivering said successive stitches to the severing device, and means to control said delivering means, whereby a predetermined length of stitches beyond the edge of the material is formed before the severing takes place.

12. In a sewing machine a bed plate, stitch-forming mechanism for stitching articles and forming a chain of stitches between successive articles, a constantly operated cutting device, means for causing the same to act upon the chain of stitches at predetermined times, and means to feed said chain forward, said bed plate being provided with means to allow the cuttings of thread to be carried away from the stitch-forming mechanism and cutter.

13. In a sewing machine, stitch-forming mechanism, a cutting device, means to operate it, means to deliver the thread to the cutting device, and automatic means to raise the thread-delivering device before the material passes under its thread-engaging end.

14. In a sewing machine, stitch-forming mechanism, a cutting device and means for operating it, means for delivering the thread to the cutter, a device riding on the fabric, operative connections between the device in contact with the fabric and the thread-delivering means.

15. In a sewing machine, stitch-forming mechanism, feeding mechanism, a cutting device located at one side of the line of feed and means to operate it, means acting on the chain of stitches to prevent their being drawn back by the motion of the feeding device, and means for delivering said chain to the cutting device.

16. In a sewing machine, stitch-forming mechanism, feeding mechanism including a feed dog, a cutting device, and means to operate it, means to clamp the thread while the feed dog is below the top of the bed plate and release it when said feed dog rises above it, and means for delivering the thread to the cutting device.

17. In a sewing machine, stitch-forming mechanism, feeding mechanism including a feed dog, a presser foot and its supporting bar, a thread-clamping device receiving motion from the rise and fall of the feed dog,

and means to raise said presser foot and clamping device together.

18. In a sewing machine, stitch-forming mechanism, a feeding mechanism, a cutting device and means to operate it, a device acting to deliver the thread to the cutter, said feed mechanism including a two part feed member, the rear portion having a vertical slot for the reception of the device acting upon the thread.

19. In a sewing machine, stitch-forming mechanism, a feeding mechanism, a cutting device and means to operate it, said feeding mechanism including a two part feed dog, one part arranged in advance of the cutter and the other in rear thereof and means for delivering the thread to the cutting device controlled by the article being stitched and means for imparting the usual four motions to the feed dog.

20. In a sewing machine, stitch-forming mechanism, a feeding mechanism, a cutting device, said feeding mechanism including a two part feed member, one part arranged in advance of the cutter and the other in rear thereof, and a movable device for delivering the thread into the path of the cutting device.

21. In a sewing machine, stitch-forming mechanism, and feeding mechanism, a cutting device and means to operate it, a presser foot, said feeding mechanism including a two part feeding device located one in advance of the other and between which said cutting device operates, said presser foot coöperating with both parts of the feed to carry the material clear of the cutter and means controlled by the article being stitched to deliver the material to be severed to the cutter.

22. In a sewing machine, stitch-forming mechanism, a cutting device and means to operate it, a device acting to deliver the thread to the cutter, said device being normally held spring pressed in engagement with the thread.

23. In a sewing machine, stitch-forming mechanism, a cutting device and means to operate it, a device acting to deliver the thread to the cutting device, said thread-delivering device being normally held spring pressed in engagement with the thread, and means for controlling the movement of the thread-delivering device.

24. In a sewing machine, stitch-forming mechanism, a suitable presser foot, a cutting device, and a device acting on the chain of stitches to carry the same to the cutter, and means whereby the presser foot and chain-carrying device are elevated together.

25. In a sewing machine, stitch-forming mechanism, a suitable presser foot, a cutting device, means acting on the chain of stitches to carry the same to the cutter, an auxiliary device independent of the presser

- foot, for engaging the chain of stitches, and means whereby the presser foot, chain-carrying device and auxiliary device acting on the fabric are elevated together.
5. 26. In a sewing machine, stitch-forming mechanism, a suitable presser foot, a cutting device, means acting on the chain of stitches to carry the thread to the cutter, a single lever to raise the presser foot, and chain-carrying device above the cloth plate.
10. 27. In a sewing machine, stitch-forming mechanism, and a top feeding device, a presser foot, a cutting device and means to operate it, and a thread-delivering device for carrying the thread to the cutter, and means for simultaneously raising the top feeding device, presser foot and thread-delivering device.
20. 28. In a sewing machine, stitch-forming mechanism, and a top feeding device, a presser foot, a cutting device and means to operate it, a clamping device acting upon the chain of stitches, a device for delivering the thread to the cutter, means for simultaneously raising said top feeding device, presser foot, thread-clamping device and said thread-delivering device.
30. 29. In a sewing machine, stitch-forming mechanism, a cutting device and means to operate it, a clamping device acting upon the thread, a device for delivering the thread to the cutter, said thread-clamping device being pivoted to a stationary part of the machine frame, and means whereby the 35 said thread-clamping device is elevated above the work plate.
40. 30. A sewing machine having chain stitch-forming mechanism and a continuously operable thread cutter, and means for engaging the loose chain between successive articles and forcing the same into the path of the cutter.
45. 31. A sewing machine having chain stitch-forming mechanism and a continuously operable thread cutter, and a fabric-controlled depressing means for engaging the loose chain between successive articles and forcing the same into the path of the cutter.
50. 32. A sewing machine having stitch-forming mechanism and a continuously operable thread cutter, and a thread-depressing member having a slot for the passage of the cutter.
55. 33. A sewing machine having stitch-forming mechanism, a slotted fabric-supporting plate, a thread cutter arranged below the slot, and means for forcing the loose thread downward through the slot, into the 60 path of the cutter.
65. 34. A sewing machine having stitch-forming mechanism, a slotted fabric-supporting plate, a continuously operable thread cutter below the slot, and an automatic means for forcing the loose thread
- downward through the slot into the path of the cutter.
35. A sewing machine having stitch-forming mechanism, a slotted fabric-supporting plate, a continuously operable 70 thread cutter arranged below the slot, and a fabric-controlled means for forcing the loose thread downward through the slot into the path of said cutter.
36. A sewing machine having stitch-forming mechanism, a slotted fabric-supporting plate, a continuously operable cutter arranged below the slot, a thread-depressing foot operating through said slot, and a fabric-supported member serving to hold 80 said foot in elevated position while fabric is passing under said member.
37. A sewing machine having stitch-forming mechanism, a thread cutter, a fabric-supporting plate having a slot, the plate being disposed above the cutter, a pivotally mounted arm having at its free end a thread-engaging and depressing foot, and a cloth-supported member carried by said arm and serving to maintain the foot in elevated position during the passage of fabric beneath 90 said member.
38. A sewing machine having stitch-forming mechanism, a slotted fabric-supporting plate, a thread cutter arranged below the 95 slot, said plate being further provided with a recess or depression over which the fabric passes, a pivotally mounted arm having at its free end a thread-engaging and depressing foot, and a cam-shaped member carried 100 by said arm and riding on the fabric bridged over said recess or depression.
39. A sewing machine having stitch-forming mechanism, a slotted fabric-supporting plate, a pivotally mounted arm having at its 105 free end a thread-engaging and depressing foot slotted to permit bridging of the thread, a thread cutter arranged below the slot of the plate and arranged to pass through the slot of the foot, and a cloth elevated member 110 carried by said arm and normally holding the thread-depressing foot inoperative.
40. A sewing machine having stitch-forming mechanism, a top feed bar having a slot, means for operating the same, a fabric-supporting plate also provided with a slot, a thread cutter arranged below the fabric-supporting plate, and a thread-engaging and depressing member operating through both 115 slots to depress the thread into engagement with the cutter.
41. A sewing machine having stitch-forming mechanism, a slotted fabric-supporting plate, a thread cutter arranged below the plate, a top feed bar having a longitudinal 125 slot, means for raising and lowering said top feed bar, a pivotally mounted arm supported by the presser bar and having at its free end a thread-engaging and depressing member operating through the slot of the 130

feed bar, a cloth supported member carried by said arm, a second arm supported by a fixed portion of the frame and arranged to engage with the pivoted arm, and a cam carried by the presser bar and engaging said second arm to effect positive upward movement of the thread-depressing arm when the presser foot and top feed are raised.

42. A sewing machine having stitch-forming mechanism, a slotted fabric-supporting plate, a thread cutter arranged below the plate, a presser foot, a top feed bar having its forward end guided by said presser foot, a presser bar, an auxiliary presser bar connected thereto and guided by the frame, a lug projecting from the auxiliary presser bar, a toe extending from the upbent end of the top feed and engaging said lug, a rocker arm having a pivotal connection with the top feed and serving to transmit movement thereto, a thread-engaging and depressing arm carried by the presser bar, a second arm pivoted to the frame, and a cam carried by the presser bar and engaging said second

arm to effect movement of both arms to elevated position and the interlocking of said arms when elevated.

43. In a sewing machine, a presser foot, a cutting device and means to operate it, automatic means for rendering said cutter effective or ineffective, said means rising and falling with said presser foot as the amount of material under it varies.

44. In a sewing machine a feeding mechanism, a cutting device, means for operating said cutting device continuously, automatic means independent of said feeding mechanism for causing a relative movement between said cutting device and the material to be cut for rendering said cutting device effective or ineffective.

In testimony whereof I affix my signature, in presence of two witnesses.

DUDLEY S. SEYMOUR.
